[57] CLAIM

The ornamental design for a chair, as shown and described.

DESCRIPTION

FIG. 1 is a right-front perspective view of a chair showing my new design;

FIG. 2 is a front perspective view;

FIG. 3 is a rear perspective view; and,

FIG. 4 is a right side perspective view, the left side being a mirror image thereof.

The design of the fabric covering the seat and backrest forms no part of the claimed design.
